US0D1022600S

(12) **United States Design Patent** (10) Patent No.: **US D1,022,600 S**
(45) Date of Patent: ** Apr. 16, 2024

(54) **WATER BOTTLE**

(71) Applicant: **Zhejiang Fullstar Houseware Co., Ltd.**, Taizhou (CN)

(72) Inventor: **Congqiang Lu**, Zhejiang (CN)

(**) Term: **15 Years**

(21) Appl. No.: **35/515,314**

(22) Filed: **Sep. 23, 2022**

(80) **Hague Agreement Data**

Int. Filing Date: **Sep. 23, 2022**

Int. Reg. No.: **DM/223736**

Int. Reg. Date: **Sep. 23, 2022**

Int. Reg. Pub. Date: **Oct. 7, 2022**
